UNITED STATES PATENT OFFICE.

BENJAMIN F. MAYO, OF SALEM, MASSACHUSETTS, ASSIGNOR, BY MESNE ASSIGNMENTS, TO THE UNITED SHOE MACHINERY COMPANY, A CORPORATION OF NEW JERSEY.

MACHINE FOR DRIVING PROTECTORS.

SPECIFICATION forming part of Letters Patent No. 768,811, dated August 30, 1904.

Application filed September 8, 1899. Serial No. 729,829. (No model.)

To all whom it may concern:

Be it known that I, BENJAMIN F. MAYO, a citizen of the United States, residing at Salem, in the county of Essex and State of Massachusetts, have invented an Improvement in Machines for Driving Protectors, of which the following description, in connection with the accompanying drawings, is a specification, like letters on the drawings representing like parts.

This invention is intended as an improvement on the class of machine represented in Letters Patent of the United States No. 741,522, granted October 13, 1903, said patent showing and describing a machine for inserting "protectors" or "protective slugs," as they are therein styled, into the heels or soles of boots or shoes, said machine being adapted to drive protectors of varying shapes, some of which are therein shown.

The machine of this application is shown as adapted to drive protectors of rectangular shape; but, as explained in said United States Patent No. 741,522, the machine may readily be changed so that protectors of different shapes may be driven. In said patent the protectors are shown as guided by a fin forming a raceway, each protector riding on said fin to the delivery end of the raceway, each protector as it arrives at the end of the raceway being deposited on a smooth surface forming a part of a movable carrier provided with a space or recess, which the protector is expected to enter; but sometimes it happens that a protector fails to enter the said space or recess correctly, owing to the fact that in the movement of the carrier one edge of the recess comes first under one part, wing, or half of the protector and then under the other, so that the unsupported part or wing of the protector may start to enter the recess while the other part or wing rests on the top surface of the moving carrier at one side of the recess, and consequently the protector is liable to be partially overturned.

The use of the machine referred to has demonstrated the great desirability of maintaining perfect control of the protectors from

the time that they enter the raceway up to the time they are acted upon by the driver to be driven into the stock, for it will be understood that the protectors must be driven into the stock accurately, so that their wings or open ends will occupy exactly the desired predetermined position; otherwise the figure or pattern made by driving the protectors will lack uniformity in general appearance or will be distorted or marred.

Herein I have made the carrier in two parts, movable with relation to each other, thus making it possible to enlarge the protector-receiving space in the carrier when the latter comes into position under the raceway, thus enabling the protector to drop easily into said space. The parts of the carrier are then brought together to clamp the protector while the carrier is moved to put the protector in position to be driven.

The carrier is provided with an inner guide which occupies a position in the space of the carrier and is straddled by the protector lying therein; but herein the said inner guide is represented as somewhat longer to project farther into the space formed by the wings of the protector.

The raceway herein employed may be like the one shown in said United States Patent No. 741,522 or one adapted to guide and keep said protectors from rotating indiscriminately during their passage toward the delivery end thereof, at which point, while the protectors straddle the positioning portion and are surrounded by a lip, instead of letting the protectors off one at a time upon the top of the moving carrier, as therein provided for, I have provided at the end of said raceway means whereby it is possible to insure that the protectors leave the raceway or positioning portion without turning or twisting, the best form of which now known to me consists of a device which I have designated as a "protector-sustainer," on which the endmost protector of the series may descend and rest while yet under the control of the positioning portion of the raceway, each protector in succession coming to and being held by said pro-

tector-sustainer until the carrier, having the recess for the reception of the protector next to be driven, is actuated to put said recess in vertical alinement with the delivery end of the raceway and immediately under the protector next to enter said recess. When the carrier is in this position, the protector-sustainer is quickly actuated to release the protector, so that it may leave the raceway or position portion thereof and without twisting or turning enter the recess of the carrier and straddle the inner guide thereof.

Herein it will be noticed that the sustainer represented is adapted to be operated in such manner that both wings of the protector are released substantially simultaneously, so that the protector is free to drop into the recess of the carrier.

It is necessary for good and accurate work that a protector be driven at every descent of the driver, and hence it becomes essential that a protector should enter the space of the carrier every time that said space is put in position at the delivery end of the raceway, and to insure this I have provided the machine herein to be described with an ejector which is moved whenever a protector should enter the space in the carrier, and if for any reason a protector becomes stuck at the delivery end of the raceway and does not drop in time said ejector will act on the upper end of the protector and push it instantly into the space of the carrier.

Preferably the jaws of the carrier will clamp the protector with a yielding pressure until the end of the driver, the latter having its acting end shaped to meet the protectors and straddle the inner guides and presenting a longitudinal groove at one side, meets said controlled protectors one after another and drives them from the carrier through the throat of the nose or foot plate, which is provided with an inner guide, into the stock supported on a horn, they having had no opportunity to turn or twist.

The driver herein employed is novel, it being slotted at one side, commencing at its acting end for a considerable portion of or substantially throughout its length, said slot enabling the driver to pass the inner guide of the carrier and the inner guide in the throat of the foot-plate, these inner guides extending, as already explained, for a considerable distance into the protector - passage. The driver is made adjustable, by means to be described, to not only provide for driving the protectors flush with or below or above the surface of the stock, but also to compensate for any shortening thereof by reason of wear in grinding.

Figure 1 in front elevation represents a sufficient portion of a machine for inserting protectors with my improvements added to enable my invention to be understood, the so-called "binding-block" *w* and the spring for nor-

mally closing the carrier (both shown in Fig. 4) being omitted. Fig. 1^a shows in elevation the left-hand side of the ejector, part of the positioning portion of the raceway near it, and, in section, part of the foot-plate and the plate which sustains the positioning portion of the raceway. Figs. 1^b and 1^c are similar views of the same parts in different positions. Fig. 1^d is a detail showing the dotted lip embracing the extremity of the positioning portion and its groove. Fig. 2 is a section of the raceway and its cap in the line *x*, Fig. 1. Fig. 3 is an end view of the driver; Fig. 3^a, a detail of the driver and the driver-bar and its connections, the connection and bar being in section. Fig. 4 shows the plate *D*, Fig. 1, removed and enlarged and the arms *b* and *a'* in section on the dotted line *x'*, Fig. 1, the positioning portion of the raceway being in section in the line *y*, Fig. 1^a. Fig. 5 is an enlarged end elevation of the parts shown in Fig. 4, but with the binding-block *w* removed. Fig. 6 shows the binding-block detached and with it the latch *w'*, holding the slide *D*^x. Fig. 7 is a section of Fig. 4 on the line *x'*. Fig. 8 is a view showing some of the parts represented in Fig. 4, but in different positions. Fig. 9 is a section in the line *x'*, Fig. 8. Fig. 10 shows the carrier in position to receive a protector, its jaws being open, the protector-sustainer being represented in dotted lines and being shown as open, the binding-block *w* being omitted. Fig. 11 shows the carrier closed and in its position to deliver a protector to the throat, the protector-sustainer being then in its closed position. Fig. 12 is a detail showing part of the carrier with its inner guide.

Referring to the drawings, *A* represents a column; *A'*, part of the head; *D*^x, part of the head or frame carrying the driver-bar *D*^y; *a*^z, a rock-shaft carrying an arm *a'*, having attached to its lower end a link *a*^z, engaging a stud *a*^z_x, (see Fig. 4,) extended from a carrier *a*^z, pivoted at *a*^z.

b represents an arm pivoted at *b'* eccentric with relation to the rock-shaft *a*^z, carrying the arm *a'*.

d^z_x is a block adjustable in a groove in the face of the arm *a'*, (see Fig. 4,) said block having a clamping-screw *d*^z_x, which is extended through a slot in the lever *b*, the adjustment of said clamping-screw and block longitudinally in said slots providing for the desired throw of the feed-slide *b*^z, joined to said lever *b*, the horn *C* and the plate *d* having holes *d*^x to receive suitable bolts. (Not shown.) Said bolts in practice being first extended through holes *d*^z_x in the foot-plate *D* are all substantially as shown and described in said United States Patent No. 741,522 and so do not need to be herein further specifically described.

The raceway herein shown presents a fin, the receiving end *e*^z of which is supplied with protectors from the hopper *E*, said fin be-

tween its receiving end and its delivery end or protector-positioning portion e^4 having given to it a quarter-turn, (see Figs. 1 to 1°), so that a protector 20 applied to the receiving 5 end and straddling the fin will ride thereon to said delivery end or positioning portion e^4 and during its passage will be turned into such position as to present the open end or wings of the protector toward the front of the 10 machine or in the desired established position required for the work to be done.

To prevent the protectors from jumping off the fin, a cap e^7 is provided, having its lower end widened and bent to form lips e^8 , which 15 encircle the fin and embrace the exterior of the protectors straddling the positioning portion e^4 thereof, the ends of the lips being connected to the positioning portion of the fin, as shown in Fig. 4, and having suitable openings 20 in their sides for the reception of the acting ends of the arrester and let-off. The arrester a is pivoted at a' on the plate d , and the let-off f^3 is pivoted at f' on the same plate, springs a^2 and f^3 co-operating with the said 25 arrester and let-off, as hereinafter described.

The carrier herein represented comprises a lever or moving device a^9 , pivoted at a^5 , said device having pivoted upon it at a^6 a jaw a^{10} .

The jaws a^{10} and a^{11} are each cut to form a 30 space a^{11} , Fig. 12, for the reception of a protector, said space being provided with an inner guide or tongue 31, represented (see Fig. 12) as held in position by means of a suitable screw, as 32, the two jaws being normally 35 kept closed by or through the action of a suitable spring a^{12} , the opposite ends of which engage like studs a^{13} , one extended from the part a^{10} of the carrier and the other from the jaw member a^{11} .

40 The movable jaw a^{10} has connected with and extended below it a pin a^{14} , (see Figs. 10 and 11,) which enters a slot a^{15} in the foot-plate D. When the carrier is moved from the position (see Fig. 11) where it presents a protector to 45 the action of the driver into position to receive a protector, (see Fig. 10,) the pin a^{14} of the jaw a^{10} is arrested by contact with the end of the slot a^{15} before the part a^{10} of the carrier completes its full stroke, thus effecting the 50 opening of the jaws to enlarge the space in the carrier, that a protector let off from the positioning portion of the raceway may enter said space freely and without liability of meeting the side walls thereof, the wings of the protector entering said space straddling the inner guide 31.

The part a^{10} of the carrier has a stud a^3 , which extends upwardly through a slot a^{10x} in the plate d , said stud when the carrier is moved 60 to the left, as in Figs. 4 and 10, meeting the arrester and moving it away from the positioning portion of the raceway and from contact with a protector, the stop or let-off being put at the same time into its operative position by a spring f^2 , connected with the ar-

rester, the stop coming in position at the lower end of the raceway to receive upon it the endmost protector on the raceway and hold it and all those back of it.

When the carrier is moved from the position Figs. 4 and 10 into the position Figs. 8, 75 9, and 11, the pin a^3 retires from the arrester, letting the spring a^2 actuate the arrester to meet a protector next back of the endmost protector sustained by the stop f^3 , said pin a^3 in its further movement to the right meeting said stop and moving it into the positions Figs. 8 and 9, removing the stop from below the endmost protector and letting it drop therefrom upon the protector-sustainer, to be 80 described. The arrester and stop work alternately and each is moved by the pin a^3 into its inoperative position, each being put into its operative position by a suitable spring.

The arrester herein shown operates substantially like the arrester shown in said United States Patent No. 741,522, and the stop or let-off, somewhat modified, takes the place of the so-called "ejector" in said patent, said let-off serving the purpose of a stop to temporarily support the endmost protector of the series of protectors on the raceway, while the arrester acts upon the protector next back of said endmost protector, the arrester sustaining said protector and those back of it when 95 the let-off or stop is withdrawn from under the leading end of the protector next to be delivered from the raceway into the carrier.

The carrier herein represented is moved to and fro, as provided for in said United States 100 Patent No. 741,522, it being at times moved to the left, as shown in Figs. 4 and 10, to place the protector-receiving recess thereof opposite the lower or delivery end of the raceway 105 in order that said recess may receive a protector between its open jaws, said carrier being then moved to the right into position Figs. 9 and 11 to put the protector straddling the inner guide 31, and inclosed between and clamped by the jaws of the carrier, over the 110 passage in the bushing 4^x of the foot-plate D and under the driver, so that the latter as it descends through the driver-passage d^{10} in the plate d (see Figs. 4, 7, and 9) may enter the recess in the carrier and drive the protector therefrom through the passage in the bushing 4^x into the stock S, part of which is 115 shown in Fig. 9, said stock being supposed to be sustained upon the upper end of the yielding horn or work-support C', (partially shown 120 in Fig. 1,) it being the same as the work-support shown in said United States Patent No. 741,522.

Herein the fin e^4 of the raceway to be straddled by the protectors is represented as provided at a short distance above its acting surface with a cover or cap e^7 , which overlaps the central portions of the series of protectors 125 20, some of which are shown hanging upon said fin in Fig. 1.

The protector-sustainer in the form in which I have herein illustrated it, it being one of the best forms now known to me, consists, essentially, of two members or plates 23 and 24, the member 23 being pivoted upon a stud 21, while the member 24 is pivoted upon a stud 22, said studs (represented by dotted lines in Fig. 10 and in section, Fig. 11) depending from the under side of the plate d .

10 The member 23 is represented as having a slotted space 25, and the faces of the members are normally held closed, as represented in Fig. 11, by a suitable spring 26, engaging at one end the member 23, the outer end of 15 said spring (see Figs. 1, 4, 5, 7, and 9) being connected with a stud 27, fixed at one edge of the plate d . The spring 26 acts normally to keep the members 23 and 24 closed, as in Fig. 11, said members constituting what I have 20 herein designated as a "protector-sustainer." The protector-sustainer stands normally closed at the end of the positioning portion e^4 of the fin e of the raceway, so that the endmost protector 20 (see Fig. 9) straddling said 25 positioning portion is permitted to drop therefrom on the withdrawal of the let-off f^3 , the arrester a at such time acting against one side of the protector next above the endmost protector of the series, as represented in Figs. 8 30 and 9. The protector-sustainer receives upon it and supports, as shown, the lower end of the protector while the carrier is in the position shown in Fig. 9 and 11, the jaws of the carrier through the spring a^2 then clamp- 35 ing or holding a protector in position to be driven therefrom through the protector-passage in the throat of the foot plate or block as the driver 28 to be described descends.

After the driver-bar or carrier D^5 has been 40 operated to drive a protector and has risen into its elevated position the carrier is moved from the position shown in Figs. 9 and 11 to the left into the position Figs. 4, 5, 7, and 10, and during this operation the pin a^3 meets 45 not only the arrester, but also the member 24 of the sustainer, turning said member 24 about its stud 22, causing the corner 29 of said member, acting against a part of the member 23, to move the member 23 in substantial unison 50 with the member 24, but in an opposite direction, so that the acting faces of said members which may contact substantially under the end of the raceway are separated or moved, as herein represented, in opposite directions, 55 enabling the endmost protector to be instantly released, that it may leave the protector-sustainer and positioning portion e^4 (see Fig. 7) and without twisting or turning enter the recess a^3 (see Figs. 5, 7, and 10) of the then open 60 jaws of the carrier, it being understood that as the carrier was moved to the left, as described, from the position Fig. 11 into the position Figs. 7 and 10, the pin a^6 , extended from the jaw a^4 , met the end of the slot a^4 65 and arrested the said jaw a^4 , while the portion

a^4 of the carrier continued to move, thereby enlarging the recess in the carrier for the ready admission of the protector, it straddling the inner guide 31 therein.

It is essential that the protector be guided 70 or controlled and prevented from tipping or twisting or from turning axially in going not only from the raceway or its protector-positioning portion e^4 into the carrier, but also into position to be driven, and I have effected 75 this substantially positive control through the protector-sustainer and by providing the carrier with the inner guide 31.

The head D^4 containing the driver-bar D^5 , means for moving the driver-bar up and down, 80 and the horn are substantially the same as found in United States Patent No. 490,624, dated January 24, 1893, and in the use of the invention herein described said horn will be depressed for feeding the stock as provided 85 for in said patent, or any other similar devices may be employed, some of which put the horn automatically in a lower position when the machine is stopped. The hopper or 90 pot herein represented, and its supporting and actuating means, is supposed to be like that represented in said United States Patent No. 490,624, dated January 24, 1893.

I believe that I am the first in a machine of 95 the class herein described to make the carrier so that it may be separated as a jaw to enlarge its protector-receiving space and also the first to provide a carrier composed of jaws with an inner guide, and I also believe that I am the first to use at the end of a raceway in 100 a machine for inserting slugs or metallic fastenings an independent sustainer of any form so constructed and operated as to insure the slugs or protectors leaving the raceway without tipping, twisting, or turning, and I desire 105 to claim these new features broadly in whatever form they may be embodied or in whatever machine they may be used.

As hereinbefore stated, the pin a^3 in this 110 instance of my invention performs a double function—that is, it operates both the arrester and the let-off, as provided for in said United States Patent No. 741,522, and also the protector-sustainer. The protector-sustainer would be of very material value even were the 115 inner guide 31 of the carrier omitted.

To insure the proper appearance of the heel or other part of a boot or shoe provided with protectors, it is essential that the carrier be always provided with a protector, so that 120 a protector may be driven at every operation of the driver. Ordinarily the protector released by the stop or let-off will drop properly upon the sustainer, and the latter will 125 then release the protector and let it drop by gravity into the then open space of the carrier, and said protector will be arrested in said recess by the upper side of the foot-plate; but occasionally the protector will stick or get clogged, so that it fails to drop from the 130

end of the protector-receiving portion of the raceway into the open space of the carrier, and to prevent this I have provided the machine with an ejector which will act positively to put the endmost protector of the series of protectors—viz., the one below that acted upon by the arrester—into the open space of the carrier. This ejector in the form in which I have herein represented it consists, essentially, of a lever t , pivoted upon a stud t' , carried by an ear or projection t^2 of a slide-bar t^3 , said slide-bar being slotted at its upper end, as at t^4 , to embrace a stud t^5 , extended from a near t^6 , suitably held in the head D^4 .

15 The slide-bar has a pin t^7 , which enters a slot t^8 in the end of a radius-bar t^9 , pivoted at t^{10} , on the usual back plate or stationary part t^{12} of the rotating hopper or protector-pot E^9 , common to said United States Patent No. 741,522, said hopper being sustained upon an arm E^8 , suitably pivoted at its inner or right-hand end upon the framework of the machine. The radius-bar t^9 has a projection t^{14} , and a suitable spring t^{15} , connected with said radius-bar and with a stud t^{16} of the head D^4 , normally acts to lift said radius-bar and the slide-bar t^3 , keeping the projection t^{14} of said radius-bar in the range of movement of a cam projection t^{17} , forming part of the usual disk connected with the main shaft of the machine—a shaft which may be substantially such as the shaft marked C^9 in said United States Patent No. 490,624, dated January 24, 1893—it carrying a cam projection t^{18} to meet the block t^{19} , connected with the driver-bar, to lift it in usual manner. The cam projection t^{17} is extended by a cam-surface t^{20} , which extends for about one hundred and twenty degrees of a circle. The lower end of the ejector t is squared and shaped to present a toe projecting from one edge of the ejector below a recess t^{22} , a spring t^{23} , connected with said ejector, normally acting to keep the toe at the lower end of the ejector in contact with the lip e^8 , surrounding the lower end of the protector-positioning portion e^{14} of the raceway, which terminates in an opening t^{24} in the plate d , said positioning portion having at that side or edge straddled by the protector $5c$ a groove, as t^{25} .

Fig. 1 shows the ejector in its most elevated position, the projection t^{17} just above and in contact with the projection t^{14} ready to depress the radius-bar t^9 and impart downward movement to the slide-bar t^3 from the position Figs. 1 and 1^a. The projection depresses the slide-bar and moves the ejector from the position Fig. 1^a into the position Fig. 1^b, the lower end of the ejector entering a notch t^{26} in said lip and the groove t^{25} in the positioning portion, said ejector stopping in its downward movement at a point substantially flush with the upper side of the carrier, thus meeting the endmost protector in case the latter 65 should be caught in any way. The protector-

sustainer having been put into position to afford a passage for the protector into the space of the carrier and the ejector having acted to push the protector into said space, the spring t^{15} immediately elevates the ejector into the position Fig. 1^c, the part t^{20} of the cam acting against the part t^{14} of the radius-bar to retain the ejector in this position until the arrester has engaged the protector next to the endmost protector on the raceway.

The ejector operates while the carrier is in the position Fig. 10, and in such position it will be understood that the stop acts to hold back the series of protectors next back of the one which was deposited upon the closed sustainer when the sustainer and carrier occupied the position shown in Fig. 11, and when the ejector acts it will be understood that the arrester occupies the position Fig. 4. As the ejector rises from the position Fig. 1^c, it being supposed that a protector has been properly put into the recess of the carrier and the carrier closed and started in its movement to the right from Fig. 10 into the position Figs. 9 and 11, the arrester acts to meet the protector next back of the one sustained by the stop and hold the column of protectors against vertical displacement while the ejector completes its ascent. The ejector having arrived at its highest position, the stop or let-off f^3 is moved by the pin a^3 , letting the endmost protector on the positioning portion and sustained by said stop drop upon the sustainer, the arrester serving to hold the protector acted upon by it and all those back of it.

The driver 28 herein shown is provided, commencing at its acting end, with a longitudinal recess 33. (Shown best in Fig. 3, where the driver is represented in end view, said recess being also shown by dotted lines in Fig. 1.) The recess in the driver is rendered necessary by the use of the long inner guides 31 and 31^a, referred to, said guide or guides standing between the wings of the protector when the driver descends to meet the protector and drive it. During the operation of the driver in driving a protector the groove 33 travels over the said inner guide or guides. The driver runs in a driver-guide 34, secured in suitable manner to a part of the framework, as by screws 35. The upper end of the driver has a shank provided with a screw-threaded portion 36, which engages the screw-threaded interior of a sleeve 37, the upper end of the shank entering a hole in the end of the driver-bar, where it is locked in position by means of a set-screw 38. By loosening the screw 38 and turning the sleeve 37 these threads acting on the threads of the shank 36 of the driver enable the position of the driver to be adjusted vertically, so that it may be lowered, as desired, to compensate for wear of the driver due to grinding, to adjust the driver to drive the protectors farther into the stock, or to remove the driver in case it be broken,

in which instance the driver may be ground again to shape or be shortened, and it may be again applied quickly to the driver-bar.

The foot-plate D is shown as provided with a removable slide D^x, represented (see Figs. 4 to 11) as dovetailed in cross-section and entering a dovetailed groove in said foot-plate. This slide normally stands below the end of the raceway and covers a hole w⁴, (shown by dotted lines,) made in the under side of the foot-plate, and when it is desired to take off any protectors on the raceway the slide may be removed, affording ready access to the raceway. To keep this slide always in its proper position, there is applied to the front end of the plate d a binding-block w, which is confined to said plate d by screws w^x. The front side of the binding-block has a latch w² pivoted thereon at w³ and having a notch to fit the reduced end of the slide D^x. When it is desired to remove the slide in order that any protectors on the raceway may be taken off through the hole w⁴, the operator lifts the latch w² and withdraws the slide.

Having described my invention, what I claim as new, and desire to secure by Letters Patent, is—

1. A raceway to receive a winged protector and present the same at the delivery end thereof, a recessed carrier movable in a plane below the delivery end of said raceway, and means to enlarge the recess of the carrier below the endmost protector to be taken from the raceway, that said protector may drop into the recess of said carrier, and means to thereafter contract said recess and clamp the protector therein.

2. A raceway having at its delivery end a protector-positioning portion to enter the open space of a protector, a recessed carrier presenting a yielding member at one side of its recess, means cooperating therewith to move said yielding member to enlarge the recess of the carrier when opposite the end of said positioning portion for the reception of a protector in said recess, means to insure the delivery of a protector from said positioning portion into the recess of the carrier, and means to move the carrier to convey the protector into position to be driven.

3. A raceway having at its delivery end a protector-positioning portion to enter the open space of and place the wings of a protector in a defined position, a carrier having a spring-actuated jaw adapted to receive, clamp and maintain a protector in upright position, a foot-plate having a passage for a protector, a driver-bar and driver, and means to move said carrier containing a protector in upright position, putting said protector in position under the driver to be driven into the stock.

4. In a machine of the class described, the following instrumentalities, viz., a raceway to support and guide protectors to the delivery end thereof, a movable carrier presenting jaws

provided with a recess to receive and surround a protector, independent devices to insure the delivery of said protectors from said raceway one at a time into the recess of said carrier; means to move said carrier; a foot-plate having a passage and an inner guide to receive and control a protector from said carrier, a support for the stock, a driver, and means to operate it to drive said protector from said carrier and foot-plate into the stock.

5. A carrier having an inner guide to enter between the wings of a protector, combined with a driver shaped to bear upon the wings of the protector and adapted to pass said guide as the driver descends.

6. A carrier having a recess to receive a protector and having an inner guide, and means to cause said carrier to clamp a protector in said recess.

7. A carrier having positive means to hold a protector and having a guide to enter the space between the wings of the protector.

8. In a machine for inserting protective slugs into the soles or heels of boots or shoes, a raceway, a device to transfer slugs from the raceway into position to be driven, said device presenting at its acting end jaws provided with recesses in their coacting faces, and an inner guide in the recess between said jaws, said guide entering the space between the wings or open ends of the slugs.

9. A movable carrier presenting jaws having a protector-recess and an inner guide; one of said jaws being movable with respect to the other combined with a driver to drive a protector from said carrier.

10. A carrier having a protector-receiving recess, and an inner guide; combined with a driver shaped to partially surround said guide as it acts to drive a protector from said carrier.

11. In a machine for inserting protectors having laterally-extending wings, means to guide a protector while it is being driven, said means having a tongue to enter and fit loosely between the wings of the protector, and a driver having a longitudinal recess, said tongue entering said longitudinal recess as the driver descends.

12. In a machine for inserting protectors having laterally-extending wings, a foot-plate provided with a protector passage-way and a tongue projecting from one of the walls of said passage-way to enter and fit loosely between the wings of a protector, combined with a driver shaped to surround partially said tongue as the driver descends.

13. In a machine for inserting protectors, a carrier and a foot-plate, each having an inner guide to enter between the wings of a protector, and a driver having a longitudinal recess, said inner guides entering said longitudinal recess as the driver descends.

14. In a machine for inserting protectors, a driver, means to actuate the driver, a raceway,

- a protector-sustainer having provision for supporting the lowermost protector on the raceway and for insuring the delivery of the protector from the raceway without twisting or turning; means independent of the driver for withdrawing the protector-sustainer and to allow the protector to leave the raceway, and a transfrerer for moving the released protector into position to be driven.
15. A machine for inserting winged protectors, comprising a raceway arranged to deliver the protectors with their wings extending horizontally, a device at the end of said raceway to support the wings of a protector, said device comprising a plurality of parts, and means to separate the parts of said device under the protector to insure the protector leaving the raceway without turning or twisting.
20. A raceway to guide protectors having laterally-extending wings, a carrier provided with a guide, a multipart protector-sustainer located at the end of said raceway, and means to move the parts of said protector-sustainer to enable a protector to drop from the raceway onto the carrier with its wings encircling said guide.
25. A raceway and a protector-sustainer located at the end thereof, said sustainer being composed of two movable plates, a spring to normally close said plates, and means to move one of said plates positively, said plate, in its movement, moving the other away from it to afford a space between said plates for the passage of a protector.
30. A raceway for guiding a series of protectors, a protector-sustainer located at the end of said raceway and consisting of a plurality of parts normally closed under the end of the raceway to sustain the lower edge of the endmost protector thereon, combined with means to separate said parts to withdraw them from below the lower end of the raceway and permit the endmost protector to leave the raceway.
35. A raceway to guide protectors, and a carrier having an inner guide to receive said protectors; combined with a protector-sustainer located at the end of said raceway and acting normally to sustain the endmost protector of the line of protectors controlled by said raceway; and means to move said protector-sustainer to enable the protector sustained by it to be delivered to the carrier.
40. A raceway to guide protectors having laterally-extending wings, and a carrier having a recess to receive said protectors, combined with a protector-sustainer; comprising a plurality of parts, located at the end of said raceway and acting normally to sustain the endmost protector of the line of protectors controlled by said raceway; and means for simultaneously moving the parts of said protector-sustainer to enable a protector to drop into said recess.
45. In a machine of the class described, a raceway having at its delivery end a positioning portion, a protector-sustainer occupying a position at the end of said positioning portion to sustain a protector, a carrier having a recess for the reception of a protector, combined with an ejector to act directly upon the protector sustained by the protector-sustainer and put it into the recess of the carrier.
50. In a machine of the class described, a raceway having at its delivery end a positioning portion, a plate to which the lower end of said portion is secured, said plate having an opening through it, an ejector, and means to move it up and down in said opening.
55. In a machine of the class described, a raceway having a protector-positioning portion to guide a series of protectors, said portion having a longitudinal groove at or near its lower end and a plate having a slotted lip surrounding the lower end of said portion, combined with an ejector to enter the slot of the lip and the groove of the positioning portion and meet in its downward movement the upper end of a protector.
60. In a machine of the class described, a raceway having at its delivery end a protector-positioning portion, a carrier having a pivoted jaw, means to move the carrier and open the jaw below said positioning portion to receive a protector, and an ejector to act against a protector and force it into position between said open jaws.
65. In a machine of the class described, a carrier having a protector-recess, a raceway to guide protectors, an arrester, and a let-off to control the delivery of the protectors singly, and an ejector to act on the protector from which the let-off has retired to push it into the recess of the carrier.
70. In a machine of the class described, a foot-plate, a raceway having a fin to receive and guide protectors, means to deliver said protectors from said raceway, one at a time; combined with a carrier movable toward and from the raceway and having jaws, one of the jaws thereof having a pin, and means to engage said pin before the completion of the movement of the carrier toward the raceway to open said jaws for the reception of a protector, and a device acting normally to close the jaws when permitted to act.
75. In a machine of the class described, a raceway having at its delivery end a positioning portion, an arrester adapted to act on the protector next to the endmost protector on the raceway, and means for moving the arrester to release the protector, a carrier having a recess to receive a protector and movable below the end of said positioning portion, combined with a vertically-movable ejector, means to move the ejector in one direction to effect the discharge of a protector into the carrier, means thereafter to move the ejector in an opposite direction and means for holding the ejector temporarily adjacent to the lower end of said

positioning portion, said last-named means being adapted to allow the ejector to complete its upward stroke and stop it in a position to engage at its next descent the upper end of the next protector to be taken from the race-way and put into the carrier.

5 In testimony whereof I have signed my name

to this specification in the presence of two subscribing witnesses.

BENJAMIN F. MAYO.

Witnesses:

GEO. W. GREGORY,
MABEL PARTELOW.

Corrections in Letters Patent No. 768,811.

It is hereby certified that in Letters Patent No. 768,811, granted August 30, 1904, upon the application of Benjamin F. Mayo, of Salem, Massachusetts, for an improvement in "Machines for Driving Protectors," errors appear in the printed specification requiring correction, as follows: On page 2, line 74, the word "dotted" should read *slotted*, and on page 3, line 57, the reference letter and numeral "*d⁴⁹*" should read *a⁴⁹*; and that the said Letters Patent should be read with these corrections therein that the same may conform to the record of the case in the Patent Office.

Signed and sealed this 27th day of September, A. D., 1904.

[SEAL.]

F. I. ALLEN,
Commissioner of Patents.
